UNITED STATES PATENT OFFICE.

EUGENE H. LESLIE, OF LOS ANGELES, CALIFORNIA, ASSIGNOR TO GENERAL PETROLEUM CORPORATION, A CORPORATION OF CALIFORNIA.

METHOD AND APPARATUS FOR USING REAGENTS IN THE REFINING OF PETROLEUM OILS.

1,310,164.

Specification of Letters Patent. Patented July 15, 1919.

Application filed September 25, 1917. Serial No. 193,199.

To all whom it may concern:

Be it known that I, EUGENE H. LESLIE, a citizen of the United States, residing at Los Angeles, in the county of Los Angeles and State of California, have invented a new and useful Method and Apparatus for Using Reagents in the Refining of Petroleum Oils, of which the following is a specification.

The invention consists in the construction and novel arrangement and combination of parts hereinafter described, illustrated in the accompanying drawings and pointed out in the claims hereunto appended.

My invention relates to the art of refining petroleum oils. In that art, it is common practice to subject the oil to the action of various reagents, such as acids and alkalis.

The principal object of my invention is to provide a method by which the amount of said acids and alkalis which is required for the refining of a given body of oil may be greatly reduced.

A further object of the invention is to provide an apparatus which can be readily manipulated to produce considerable savings in the amount of reagent used.

Referring to the drawings, which are for illustrative purposes only:

Figure 1 is a side elevation of a preferred embodiment of my apparatus.

Fig. 2 is a plan view of the same apparatus.

Fig. 3 is a section on a plane represented by the line 3—3 of Fig. 1.

Fig. 4 is an elevation, partly in section, showing the nozzle used in my invention.

In the apparatus shown in these drawings, an acid tank 11, an acid wash tank 12, an alkali tank 13, and an alkali wash tank 14 are shown. An acid sludge receptacle 15 and an alkali receptacle 16 are also shown, the fluids from the various apparatus being handled through a primary pump 17 and a secondary pump 18. The oil to be treated is admitted through a pipe 19 and the treated oil is removed through a pipe 20. Air under pressure may be admitted to the receptacle 15 through a pipe 21 controlled by a valve 22, and acid may be admitted to the receptacle 15 through a pipe 23 controlled by a valve 24. Water may be supplied to the tanks 12 and 14 through a pipe 25.

The acid tank 11 consists of a tight shell having a top 30 into which an acid pipe 31 connects, this acid pipe 31 being connected through a union 32 with a pipe 33 terminating in a nozzle 34 having small openings therein as shown in Fig. 4. The pipe 33 passes through a stuffing box 35 secured in a nipple 36 secured in the top of the tank 30, the parts 32 to 36 being best shown in Fig. 4. A safety valve 37 arranged to open when subjected to predecided upon pressure is also provided in the top 30. The bottom of the tank 11 connects through a fitting 38 with an oil drainage pipe 39 in which a valve 40 is placed.

The fitting 38 also connects with the receptacle 15 through an acid sludge pipe 41 having a valve 42. The acid sludge pipe 41 connects into the top of the receptacle 15 which is in the form of a tight shell having a gage glass 43 on the side thereof. Connected into the bottom of the receptacle 15 is a fitting 44 which connects with a pipe 45 having a valve 46 therein, and with a drain pipe 47 having a valve 48 therein. The pipe 47 discharges into a drain 49. The pipe 45 connects with the acid pipe 31 previously described.

The pipe 39 is connected through a pipe 50 having a valve 51, with a suction fitting 52 on the primary pump 17. The oil supply pipe 19 is connected through a valve 100 with a fitting 101 which is connected with the suction fitting 52 through a valve 53. A pipe 55 which connects into the top of the acid tank 11 is connected to the fitting 101 through a valve 54. The pipe 39 is also connected through a valve 56 with a pressure pipe 57 connected to the pressure side of the pump 17. The pressure pipe 57 is also connected through a valve 58 with a pipe 59 connected to a perforated pipe 102 in the bottom of the acid wash tank 12.

The acid wash tank 12 consists of a tight shell having a gage glass 60 near the bottom thereof and having a top 61 into which a nozzle 62 projects, this nozzle being similar to that shown in Fig. 4 and being connected through a valve 65 with the water pipe 25. Headers 63 are connected into all three of the tanks 12, 13 and 14. The headers 63 are carried up for a considerable distance, and

are open to the air at their upper end for the purpose of providing a gas vent and at the same time maintaining a sufficient head on the tanks. A drainage pipe 70 controlled by a valve 71 is provided in the bottom of the tank 12, discharging into the drain 49. A pipe 72 is connected into the top of the acid wash tank 12, being carried down and connected to a perforated pipe 105 in the bottom of the alkali tank 13.

The alkali tank 13 consists of a tight shell having a gage glass 73 near the bottom thereof, and having a tight top 74 into which a nozzle 103 similar to that shown in Fig. 4, projects, this nozzle being connected to an alkali circulating pipe 75, this pipe 75 being also connected with a pressure pipe 77 connected to the pressure side of the pump 18. The pipe 77 is also connected through a valve 78 with the top of the alkali reservoir 16. The bottom of the alkali reservoir 16 is connected through a pipe 79 and a valve 80 with a suction pipe 81 which is connected to the suction side of the pump 18. The suction pipe 81 is also connected through a valve 82 and a pipe 83 with the bottom of the alkali tank 13. The top of the alkali tank 13 is connected through a pipe 84 with a perforated pipe 104 in the bottom of the alkali wash tank 14.

The alkali wash tank 14 has a tight top 85 into which a nozzle 86 is connected, this nozzle being connected through a valve 87 with the water pipe 25. The nozzle 86 is similar to that shown in Fig. 4.

The wash tank 14 is provided with a gage glass 88 and with a drain pipe 89 controlled through a valve 90, the pipe 89 discharging into the drain 49. The pipe 20 as previously explained, connects into the top of the wash tank 14 and serves to discharge the cleaned oil to any suitable tankage not shown. Located in each of the tanks 12, 13 and 14 above the perforated pipes 102, 104 and 105 are perforated diaphragms 108.

The method of operation of the invention is as follows:

The valves 54, 51, 58 and 42 being closed, the pump 17 is started and forces oil from the pipe 19 through the pipe 57 and the pipe 39 into the acid tank 11, practically filling same. The valves 47 and 48 being closed, acid is admitted to the acid receptacle 15 through the pipe 23 by opening the valve 24. When the receptacle 15 has a sufficient amount of acid in it, as indicated by the gage 43, the valve 24 is closed and the valve 48 is opened. Air under pressure is then admitted to the top of the receptacle 15 through the pipe 21 by opening the valve 22. The acid in the receptacle 15 is thus forced by the compressed air through the pipe 43 into the pipe 31, and is sprayed through the nozzle 34 into the mass of oil 65 in the tank 11. If desired, the mixture of

oil and acid can be circulated by closing the valve 100 in the pipe 19, opening the valves 53 and 54, closing the valves 51 and 58, and opening the valves 56 and 49. Oil is then taken from the top of the acid tank 11 through the pipe 55 into the pump 17 and circulated through the pipes 57 and 39 back into the tank 11. During this circulation, or before or after, the acid may be introduced as previously explained. Any excessive pressures produced by the reaction in the tank 11 are relieved by the safety valve 37. From time to time, as the acid sludge settles in the bottom of the acid tank 11, the compressed air may be shut off from the receptacle 15 and the valve 42 may be opened and portions of the sludge admitted into the acid receptacle 15, the valve 42 then being closed and the acid sludge being again introduced into the top of the acid tank 11 through the pipe 45 by means of compressed air admitted through the pipe 21 and valve 22. By the use of the acid receptacle 15 we are thus able, at will, to draw off from the bottom of the acid tank 11 any acid or acid sludge which settles therein, and we are able to reintroduce this acid or acid sludge into the top of the tank 11 so that it can again be used in the treatment of the oil therein. This results in a large saving in the amount of acid used to refine a large volume of oil.

Whenever the reaction has progressed sufficiently, the valves 58 and 56 are closed and the valves 40, 51 and 58 are opened, and the pump 17 is used to draw the mixture from the acid tank 11 through the pipes 39 and 50, forcing it through the pipe 59 and the perforated pipe 102 into the bottom of the wash tank 12. The tank 12 is partially filled with water, this water being introduced through the pipe 82 by proper manipulation of the valve 65. The oil from the pipe 59, in a finely divided condition, passes upwardly through the wash water in the wash tank 12 being broken up and distributed by the perforated diaphragm 108. The wash water tends to take into solution certain of the soluble materials and the acid which are contained in the oil, so that a layer of partially cleaned oil is maintained in the top of the tank 12. Whenever the pump 17 is put in operation for the purpose of forcing oil through the pipe 59, it also forces a portion of the previously cleaned oil from the top of the tank 12 through the pipe 72 into the alkali tank 13. The oil in the alkali tank is subjected to the action of an alkali solution which is normally contained in the alkali reservoir 16.

The valves 82 and 78 being closed, and the valves 80 and 76 being open, alkali is taken through the pipes 79 and 81 into the suction of the pump 18, and is delivered by the pump 18 through the pipes 77 and 78 to the nozzle 103 by means of which the alkali is

sprayed down through the body of the oil. The alkali settling on the bottom of the tank 13, as indicated by the gage glass 73, can be drawn out from time to time by closing the valves 80 and 76 and opening the valves 82 and 78, the alkali being thus returned to the alkali reservoir 16 by means of the pump 18. Fresh alkali can be introduced at any time into the top of the reservoir 16. Sludge may be withdrawn from the bottom of the tank 12 at any time and passed into the drain 49 through the pipe 70 by means of the valve 71.

The oil delivered to the alkali tank 13 through the pipe 72 in turn pushes oil out from the top of that tank through the pipe 84 into the alkali wash tank 14 which is exactly similar in construction to the tank 12 previously described. In the alkali wash tank 14, the oil which has been treated with the alkali is forced upwardly in a finely divided state through water contained therein, leaving through the pipe 20 as a finished product. Sludge is withdrawn and passed into the drain 49 through the pipe 89 by a suitable manipulation of the valve 90. Fresh water may be introduced into the tank 14 through the pipe 86 by a suitable manipulation of the valve 87.

30 What I claim is:

1. A method of using reagents in the treating of an oil which is lighter than the reagents, comprising the following steps: first, confining the oil to be treated in a closed vessel; second, passing the reagent downwardly through the oil in said vessel; third, collecting the reagent and the sludge formed

40 by the reagent in the bottom of the vessel; fourth, passing the material so collected through the oil so confined; and, fifth, continuously withdrawing oil from the top of said vessel and injecting it into the bottom thereof.

2. An apparatus for using reagents in the treatment of oil, comprising a closed vessel, 45 pipe means for delivering a supply of oil to said vessel, a reagent pipe through which the reagent is delivered to the top of said vessel, a reagent receptacle into which the reagent or sludge formed therefrom in said 50 vessel may be passed, means for forcing said reagent or sludge from said receptacle into said reagent pipe, and means for continuously circulating the oil to be treated through said closed vessel.

3. An apparatus for using reagents in the treatment of oil comprising a closed vessel, pipe means for delivering a supply of oil to said vessel, a reagent pipe through which reagent is delivered to the top of said vessel, 60 a reagent receptacle into which the reagent or sludge formed therefrom in said vessel may be passed, means for forcing said reagent or sludge from said receptacle into said reagent pipe, a circulating pump, pipe 65 means connecting the suction of said pump into said closed vessel near the top thereof, and pipe means connecting the pressure side of said pump to the lower portion of said vessel.

70 In testimony whereof, I have hereunto set my hand at Los Angeles, California, this 15th day of September, 1917.

EUGENE H. LESLIE.
